UNITED STATES PATENT OFFICE

THOMSON KING, OF POTTSTOWN, AND DANIEL G. BURKERT, OF BOYERTOWN, PENNSYLVANIA, ASSIGNEES TO THE PEERLESS HEATER COMPANY, OF BOYERTOWN, PENNSYLVANIA, A CORPORATION OF PENNSYLVANIA

GAS BOILER

Application filed May 21, 1928. Serial No. 279,532.

Our invention relates particularly to a gaseous fuel mixer which is of general utility, but which may be advantageously employed in a gas fired water heater or boiler of the type wherein the burner is secluded in a combustion chamber, which is substantially closed except for inlets supplying primary air thru the burner, and secondary air around the burner, and a vent outlet for the products of 10 combustion. Ordinarily the supply of gas to the burner is automatically controlled by a thermostat so as to be shut off at a predetermined temperature, but with means such as an auxiliary or pilot burner to relight the 15 main burner when the supply of gas is resumed. When the gas supply to the main burner is shut off, either thermostatically or manually, combustion may continue, at the burner, only so long as the residual fluid pressure 20 sure in the conduits for the combustible mixture of air and gas leading to said main burner is sufficient to force the mixture thru the burner jets. However, the upward draft of the products of combustion, which maintains 25 the confined atmosphere around the burner at a pressure slightly less than the outer atmosphere, quickly reduces the fluid pressure at said burner until the mixture escaping thru the burner jets diminishes in 30 combustibility, the flames lower to the jet openings, and are propagated thru said openings to the richer mixture inside of the burner, causing an instantaneous explosion of the mixture confined in the burner and the conduits 35 leading thereto which, altho of insufficient force to damage the burner or heater structure, produces a noise which is startling, and consequently highly objectionable to the occupants of the building in which the burner 40 is located.

Therefore, it is the object and effect of our improvement to prevent, or at least substantially decrease, any audible manifestation of such explosion of the combustible mixture 45 after the gas supply pressure is shut off. To that end, our invention consists in so constructing and arranging the gaseous fuel mixing elements of such a burner that, when the main supply of gas is shut off, the residue of 50 such mixture in the burner and the conduits

leading thereto is gradually consumed above the burner jet openings, without any flash back of the burner flames thru said openings.

As hereinafter described, our invention includes a gaseous fuel mixer in communication with the burner for such a heater as above described; wherein the primary air supplied for mixture with the gas, instead of being introduced to the gas stream flowing in the mixer, in the same direction as the flow of 60 gas, is introduced in the opposite direction, and preferably from, or in communication with, the confined atmosphere surrounding the burner jet openings; so that when the normal gas stream, which by its pressure normally introduces a forcible inflow of air to the burner to mix with the gas, is shut off, the air flowing thru the mixer to the burner is subjected to the same tension as the gaseous mixture flowing out thru the jet openings. 70 In other words, the draft in the confined atmosphere surrounding the burner is effective to prevent such rapid introduction of air to the burner as to permit the formation of an explosive mixture within the burner. Consequently, the rich gaseous mixture left in the burner and its conduits when the gas supply is suddenly shut off, is slowly consumed at the burner jet openings without flash back or 75 explosion.

Altho it is preferable that all of the primary air supplied to our improved mixer shall be drawn from the confined atmosphere in which the mixture is consumed, municipal supplies of fuel gas vary extensively in British thermal units. For instance such gas in Denver, Colorado, averages 320 such units; at Buffalo, New York, 800 such units; and in Northwest Pennsylvania 1200 such units. Therefore, it is practically impossible to 85 form a mixer with invariable air inlets adapting it to mix the proper amount of air with gas of such varying richness. Therefore, we prefer to provide our mixer with adjustable means to inlet air in variable quantities, from 90 the outer atmosphere, as hereinafter described.

Our invention includes the various novel features of construction and arrangement hereinafter more definitely specified.

In said drawings: Fig. I is a vertical sectional view of a gas boiler embodying our improvements.

Fig. II is a longitudinal sectional view of the gaseous fuel mixer indicated at the lower right hand corner of Fig. I.

Fig. III is a cross sectional view of the said mixer, taken on the line III, III in Fig. II.

Fig. IV is an outer end elevation of the mixer shown in Figs. I and II, as seen from the right hand end thereof, and shows the valve means for variably controlling the supply of outer atmospheric air to the mixer.

Referring to the Fig. I; the gas boiler comprises the hollow base casing 1 inclosing the combustion chamber 2. The main burner 3, which is a hollow casting having a series of burner jet orifices 4 in its upper wall thru which the gaseous mixture is supplied to the flames 5, is conveniently supported in stationary position in said combustion chamber 2, upon the cross bar 6. Said main burner is conveniently lighted by the pilot burner 8 supplied with gas thru the conduit 9. The arrangement is preferably such that said pilot burner is not controlled by any thermostatic means which may be employed to control the supply of gas to the main burner thru the conduit 10; so that the pilot burner 8 may remain lighted when the flames 5 are extinguished at the main burner.

As indicated in Fig. I; the gas is delivered from the conduit 10, to supply the main burner 3, thru the fitting 12, containing the stop cock 13, by which the flow of gas may be manually controlled. Said fitting 12 has the gas orifice nozzle 14 which determines the volume of gas in the stream emitted thru said fitting 12. Said nozzle 14 is in axial alignment with the Venturi tube 15 leading to said main burner 3, and it is to be understood that the arrangement is such that the forcible issuance of the stream of gas thru said nozzle 14 into said tube 15 normally creates a partial vacuum at the flaring mouth 16 of said tube, inducing the flow of air into mixture with the gas stream.

However, it is characteristic of our invention that the mixer casing 18 is so constructed and arranged that altho outer atmospheric air may be admitted thereto thru openings 19 at its outer face under control of the rotary valve disk 20 which has openings 21 therein, which may be brought into registry with said openings 19; said valve disk 20 may be set in such rotary position as to close said openings 19, as indicated in Fig. IV. Said valve disk 20, may be secured in any position within its range of rotary adjustment, by means of the nut 22 which is in engagement with the screw thread 23 on the said fitting 12.

An essential feature of our invention is such construction and arrangement of the mixer 18 that the primary air may be intro-

duced in a direction opposite to that of the flow of the gas supply hereto, and preferably from the interior of the combustion chamber

2. For that purpose; we provide the mixer 18 with the cylindrical tubular extension 25 which is adapted to be held in spaced relation with the perimeter of the mouth end 16 of the Venturi tube 15, by inwardly extending ribs 26, of which three are shown in Fig. III, forming three air passages 27 which are respectively in radially and circumferentially spaced relation to the axis of said nozzle 14, as shown in Figs. II and III. As best shown in Fig. II; each of said ribs is preferably provided with an abutment 28 adapted to fit against the mouth end 16 of said tube 15; to precisely determine the relative position of the gas nozzle 14, with reference to the venturi. Said tubular extension 25 of the mixer casing 18 extends thru the side wall of the boiler base casing 1, and the joint between said extension and wall may be sealed by any convenient means, such as plastic cement.

The purpose and effect of thus forming a plurality of air passages 27 in concentric relation with the axis of the Venturi tube 15 is not only to insure the uniform mixture of the primary air with the stream of gas directed thru said nozzle 14, as above described, but to insure the uniform and gradual dilution of the rich mixture remaining in the mixer casing 18 and said tube 15 when the gas is shut off and the induction of the air from the combustion chamber to said tube is effected solely by the combustion of the gradually diluted mixture in the flames 5 of the burner 3. Such construction and arrangement were adopted only after we had determined the utility and advantages thereof by considerable experimentation. It may be observed, with reference to Fig. III, that the ribs 26 which separate the circular series of air passages 27 are of considerable circumferential extent, and such extent was determined in the course of such experiments to be necessary to the proper distribution of the air with respect to the initial end 16 of the Venturi tube 15. That is to say, when said ribs 26 were reduced to the minimum circumferential extent necessary to merely hold the Venturi tube in concentric relation with the tubular casing extension 25; the consequent circumferential enlargement of said air passages 27 practically nullified the directional and uniformly distributing effect of said passages which is characteristic of the proportion shown.

The effect of the construction and arrangement above described is that the primary air introduced to mix with the stream of gas flowing to the Venturi tube 15 thru the nozzle 14, is entirely drawn from the secluded atmosphere in the combustion chamber 2, and is introduced to the mixing chamber 29

within the mixer casing 18 in a direction directly opposite to that of the flow of gas stream, as indicated by the arrows in Fig. II, but in such manner as to thoroly mix the two fluids. However, it is to be understood that the primary air thus supplied from the secluded atmosphere of the combustion chamber may be supplemented by air inlet from the outer atmosphere thru said openings 19 in the mixer casing 18, if the gas is so rich as to require such extra dilution to produce a combustible mixture. In any event, the construction, arrangement and adjustment are such that when the gas supply stream issuing from the orifice nozzle 14 is suddenly shut off, (by the thermostatic means above contemplated, or otherwise), instead of thereafter rapidly diluting the body of rich gas in the mixer 14, tube 15, and burner 3, and thus forming an explosive mixture as heretofore; the rich residual gas is thereafter only slightly diluted by mixture with sufficient air from the confined atmosphere of the combustion chamber to replace the rich mixture which slowly issues from the burner jets and is slowly consumed without any audible manifestation of its combustion.

We have found it convenient to show, in Fig. I, in cooperative relation with the gas burner above described, a water-boiler which may include a series of hollow cast iron sections 30, with flue openings 31 therethru, and connected by water conduits 32 and 33 respectively at the bottom and top thereof, said sections being held together in cooperative relation by bolts 34 and 35, extending thru lugs 36 and 37, on the sections 30. Said sections 30 are thicker at their side edges than intermediate thereof, and have spacing lugs 38 and 39, insuring that when they are clamped together by said bolts 34 and 35, with cement between said edges, they shall be in such spaced relation as to form flue passages extending vertically between said sections, and in communication with the flue chamber 40 within the casing 41 at the top of the boiler structure, which casing has the flue vent 42 leading to a chimney. In such a boiler, each section 30 preferably has a main burner 3, local thereto.

Such a boiler structure is conveniently heat insulated by the outer casing 44, and may be provided with the usual water fitting 46, carrying the gage 47; a pressure regulator 48, etc. For instance, the auxiliary air inlet 50 in said base casing 1 may be provided with the valve 51 by which it is normally closed, when said valve 51 is upheld by the chain 52 leading to thermostatic means which is operative at abnormal temperature to release said chain and permit said valve 51 to be opened by the weight 53.

However, our improved gaseous fuel mixing device may be advantageously employed

in conjunction with any suitable form of burner, regardless of the specific construction and arrangement of the details of the latter, or the form of combustion chamber in which it is operated. For instance, such a mixer may be advantageously used with a burner in the oven of an ordinary kitchen range, or other hot air chamber.

Therefore, we do not desire to limit ourselves to the precise construction, arrangement or method of operation above described, as various modifications may be made therein without departing from the essential features of our invention as defined in the appended claims.

We claim:

1. In a gaseous fuel mixer; the combination with a burner; of a combustion chamber, sealing said burner from the outer atmosphere; a gas orifice nozzle arranged to direct gas in a stream; a mixer casing inclosing said nozzle and forming a mixing chamber having an outlet for said mixture; and means for forming an air passage, arranged to introduce primary air to said mixing chamber in a direction opposite to said gas stream, and between said stream and outlet; whereby mixture of said gas and air is effected before reaching said outlet; wherein said mixer casing is located outside of said combustion chamber, but the primary air is drawn therein solely from said combustion chamber.

2. A structure as in claim 1, wherein a plurality of such air passages are separately disposed parallel with, but in radially and circumferentially spaced relation to, the axis of said nozzle.

3. A structure as in claim 1; wherein a circular series of parallel air passages is disposed in coaxial relation with said nozzle; whereby the air from said combustion chamber is divided in a plurality of small streams in uniformly spaced relation with the axis of the gas nozzle before mixing with the gas, and uniform mixture of the gas and air thereby assured.

4. A structure as in claim 1, wherein the outlet is a Venturi tube in coaxial relation with said gas nozzle, and a circular series of such air passages is formed around said tube; whereby, the air from said combustion chamber is divided in a plurality of small streams in uniformly spaced relation with the axis of the Venturi tube before mixing with the gas, and uniform mixture of the gas and air thereby assured.

5. A structure as in claim 1; also having means arranged to admit primary air in the same direction as the gas stream.

6. The combination with a Venturi tube; of a mixer casing inclosing the initial end of said tube; and means holding said tube and casing in coaxial spaced relation, including a circumferential series of ribs between them; said ribs forming a circular series of sepa-

rate air passages between said tube and casing; wherein said end of the Venturi tube terminates in a plane at right angles to its axis and said ribs have respective abutments with faces extending in a plane at right angles to the axis of said casing and in contact with said tube end; whereby said tube and casing are held in coaxial spaced relation.

In testimony whereof, we have hereunto signed our names at Boyertown, Pennsylvania, this 18th day of May, 1928.

THOMSON KING.
DANIEL G. BURKERT.
